DRAFT KEY LOCKING MEANS

Filed Aug. 6, 1925

UNITED STATES PATENT OFFICE.

LLOYD J. BROWN, OF EVANSTON, ILLINOIS, ASSIGNOR TO E. PAYSON SMITH, OF SPRINGFIELD, ILLINOIS.

DRAFT-KEY-LOCKING MEANS.

Application filed August 6, 1925. Serial No. 48,439.

My invention relates to means for locking the usual draft keys in place against accidental removal and loss; the invention contemplating means adapted to engage with 5 the tapered or tail end of the draft key and of such construction as to provide a comparatively large bearing or contact surface with the adjacent side of the center sill member or reenforcing element or cheek plate 10 secured to the center sill and therefore a construction which is adapted to withstand the strains and stresses to which it may be subjected through the back and forward movement of the draft keys at varying angles 15 en- countered in movement of the car along curves or irregularities in the right of way.

The advantages and objects of my invention will be readily comprehended from the following detailed description of the construction illustrated in the drawing, wherein:—

Figure 1 is a plan view of a portion of the center sill of a car, the coupler and portions of the draft rigging, with my improved locking means shown applied to the draft keys.

Figure 2 is a detail sectional view taken on the line 2—2 of Figure 1 looking in the direction of the arrows.

Figure 3 is an elevation of my improved locking means shown applied to a draft key which is shown in section.

Figure 4 is a perspective view of one element of the locking means.

Figure 5 is a perspective view of the end 35 of a draft key which is adapted to receive my improved locking means.

In the exemplification of the invention, the center sill members are shown at 10, 10 with their outer sides provided with reenforcing 40 or cheek plates 11 which are riveted thereto at 12 in a manner usual in car construction. The drawing, in Figure 1, also illustrates a portion of the draft rigging yoke at 13 disposed between the two center sill members 45 10, 10; the center sill member, reenforcing or cheek plates 11 and the draft rigging yoke 13 being provided with registering slots adapted to receive the draft keys shown at 14, 14. The draft keys at one end are usually

provided with a head 15 of size greater than 50 the width of the slots through which the keys pass, so that movement of the keys in one direction, beyond a certain point, is prevented by the heads 15.

The present method of retaining the draft 55 keys in place, in addition to the head 15, consists in providing the tail or tapered end 16 of the key with an aperture therethrough to receive a cotter-pin. It has been found in practice that the use of cotter-pins, or other 60 comparatively small pins, for holding the draft keys against longitudinal movement is entirely inadequate because of the constant shifting of the draft keys in a backward and forward direction induced by the forces and 65 shocks encountered and at varying angles resulting from the movement of the car around track curves or across other irregularities in the track, as for example switching back and forth; the draft rigging with the draft keys 70 at such times being subjected to enormous strains resulting from the amount of power necessary to pull the loads and which strains or impacts range as high as four or five hundred thousand pounds. The shifting or 75 movement of the draft keys causes the cotter-pins to be brought up against the center sill members or cheek plates where they are subjected to shearing strains which frequently shear off the cotter-pins and thus allow the 80 draft keys to work longitudinally in the direction of the draft key head, with the further result that the draft keys, themselves, become sheared due to the heavy impacts, thus permitting the couplers to drop out of place 85 and either result in derailments or other disasters.

My invention contemplates locking means which may be readily applied to the tail or tapered end of the draft key; the draft key 90 having its tapered or tail end 16, at a suitable distance away from the immediate end, provided with a suitable contact or abutting portion, preferably in the nature of the slots or sockets 17, 17 on both longitudinal edges of 95 the key as more clearly shown in Figure 5. The draft key may be forged with the slots 17, 17, which are adapted to receive the com-

plementary members 18, 18. The members 18, which are identical in formation, are somewhat in the nature of U-shaped castings with the ends turned outwardly as at 19; the 5 entire casting being preferably provided with a reenforcing web as at 20 along what may be termed the inner side, that is to say the side which is intended to be disposed toward the center sill or reenforcing member or cheek 10 plate secured to the same. The intermediate or U-shape portion of the casting on the side last referred to is provided on the inner perimeter or concave side with an arcuate boss or rib as at 21 conforming in curvature 15 somewhat with the curved edges of the draft key 14 or rather with the curvature of the portion within the slot 17 of the draft key; the arcuate boss or rib 21 being of width slightly less than the width of the slots 17 so 20 as to freely enter said slots. The outwardly disposed ends 19 of the U-shape castings or members 18 are each apertured so that when the correlated or complementary members 18, 18 are placed about the slotted end of the 25 draft key with the outwardly turned ends of both members 18, arranged in parallel juxtaposition as shown in Figures 1 and 3, the openings 22 in the ends 19 are in register to receive a suitable bolt as at 23 which is provided with a nut as at 24 so that when the bolts and nuts are screwed up or tightened, the complementary members 18 will be drawn together with the arcuate bosses 21 firmly seated in the slots on both sides of the draft 30 key. The complementary members 18, therefore, are firmly clamped onto the end of the draft key and are held against any movement because the vertical dimension of the opening between the complementary members 18, 18 35 is just sufficient to receive the key and as a result a twisting movement of the members about the draft key is impossible. In order to prevent possibility of the nuts 24 becoming loose and screwing off the bolts 23, I prefer to 40 provide each bolt 23 with an aperture to receive means for preventing the unscrewing of the nuts, as for example a cotter-pin as shown at 25 in Figure 3.

As is apparent from the construction 50 shown, my improved locking means can be quickly applied to the draft keys without interfering with the car underframe or draft rigging construction; it being merely necessary to provide the tail end of the draft keys 55 with an engaging surface or portion which will not interfere with its insertion through the slots in the center sill and other correlated elements, but which will permit a locking relation to be obtained between the correlated 60 members 18 and the draft key when the members have been bolted together as shown and described. That is to say, in addition to the usual head, the other end of the draft key must be provided with some contact surface 65 or cooperating formation whereby the imme-

diate end of the draft key presents a surface or portion of dimensions greater than the dimensions of the opening formed by the two complementary members 18 when the latter have been secured together.

With my construction the draft keys will not only be firmly locked in place again accidental removal, but the draft keys may be removed if necessary by simply removing the bolts 23 from the clamp members 18; while 70 at the same time means of such nature are provided as to easily withstand the strains to which it may be subjected by movement of the draft keys in a longitudinal direction so as to bring the locking means into frictional or rubbing engagement with the center sill member or its reenforcing or cheek plate.

With my construction the draft keys will not only be firmly locked in place again accidental removal, but the draft keys may be removed if necessary by simply removing the bolts 23 from the clamp members 18; while 75 at the same time means of such nature are provided as to easily withstand the strains to which it may be subjected by movement of the draft keys in a longitudinal direction so as to bring the locking means into frictional or rubbing engagement with the center sill member or its reenforcing or cheek plate.

I have shown a simple adaptation of my invention, which has been described in terms

employed merely as terms of description and not as terms of limitation, as modifications

are possible and may be made without, how-

ever, departing from the spirit of my inven-

tion.

What I claim is:

1. In combination with a draft key, the longitudinal edges of the tail end whereof are slotted, a pair of complementary U-shaped members adapted to be disposed transversely from opposite sides of the draft key, said members on their concaved sides being each provided with an inwardly extending rib adapted to seat in the draft key slots when said members are secured in place, and means whereby the ends of said members are drawn 100 together into key-engaging relation.

2. Draft key locking means, comprising, in combination with a draft key, the opposite longitudinal sides whereof are slotted a pair of complementary transversely slotted members adapted to fit about the opposite longitudinal edges of the draft key, each of said members being provided with a projection disposed into the slot beyond the inner end thereof and adapted to seat in a slot in the draft key, and means whereby said members are secured together and held in gripping relation with the draft key.

3. Draft key locking means, comprising a pair of complementary members adapted to extend about the longitudinal edges of a draft key with the opposing ends of said members arranged intermediate of the edges of the draft key, said members being provided at one side with vertical walls increasing in vertical dimensions toward the opposing ends, in combination with a draft key, the opposite longitudinal sides whereof, adjacent to the tail end, are formed to receive the inner perimeters of said members, and means 115 for drawing said members together into clamping relation with the draft key.

4. Draft key locking means, comprising, in combination with a draft key, the opposite longitudinal edges whereof are transversely 120

slotted, a pair of yoke members adapted to fit about the draft-key, said members being each provided with outwardly disposed ends adapted to be disposed perpendicular to the top and bottom faces of the draft-key, one side of each member being provided with vertically disposed walls, the inner perimeter

of each member being provided with an arcuate rib adapted to seat in the draft-key slots, and means engaging both ends of each member whereby the members are clamped together and said arcuate ribs forced into the draft-key slots. 10
